UNITED STATES PATENT OFFICE.

ALBERT T. WEISS, OF ROCHESTER, NEW YORK, ASSIGNOR TO YAWMAN & ERBE MANUFACTURING COMPANY, OF ROCHESTER, NEW YORK, A CORPORATION OF NEW YORK.

LATCH FOR FURNITURE-DRAWERS.

1,223,455.

Specification of Letters Patent. Patented Apr. 24, 1917.

Application filed December 18, 1913. Serial No. 807,494.

To all whom it may concern:

Be it known that I, ALBERT T. WEISS, of Rochester, in the county of Monroe and State of New York, have invented certain new and useful Improvements in Latches for Furniture-Drawers; and I do hereby declare the following to be a full, clear, and exact description of the same, reference being had to the accompanying drawings, forming a part of this specification, and to the reference-numerals marked thereon.

My present invention relates to furniture and more particularly to drawers and casings therefor, such as are employed in filing cabinets for office use and it has for its object to provide a simple, neat and efficient latch for holding the drawer in closed position, the improvements being directed in part toward so arranging the latch that it will in no way disfigure nor change the external appearance of the drawer. A further object of the invention is to provide a latch construction particularly adapted for use in fireproof metallic furniture having hollow walls, the invention contemplating the use of such a wall at the front of a drawer for housing the latch mechanism. To these and other ends the invention consists in certain improvements and combinations of parts all as will be hereinafter more fully described, the novel features being pointed out in the claims at the end of the specification.

In the drawings:

Figure 1 is a central vertical section through the front wall of a drawer and adjacent portions of its casing, the same being constructed in accordance with and illustrating one embodiment of my invention;

Fig. 2 is a perspective view of the lining plate of the drawer wall, the plate being viewed from the rear;

Fig. 3 is a perspective view from the front of the forward portion of the drawer body, and

Fig. 4 is a perspective view from the rear of the front plate of the drawer wall with which the body portion of Fig. 3 is interlocked.

Similar reference numerals throughout the several figures indicate the same parts.

In fireproof furniture it is particularly desirable that means be provided for locking the drawers of a cabinet in closed position as the warping effects of heat or sagging floors are apt to cause them to open by gravity and

expose the contents. In the present instance, I have illustrated my invention as embodied in a fireproof drawer of the general construction described and claimed in my companion application Serial No. 63 807,488, filed December 18, 1913, and which may comprise a front wall 1, a bottom wall 2 and side walls 3. The front wall 1 is hollow being composed of two spaced plates in the nature of a front plate 4 and a lining 65 plate 5. The latter has forwardly turned spacing flanges 6 at its bottom and sides disposed against the front plate and the front plate is provided with rearwardly and inwardly turned flanges 7 on all sides between 70 or within which the lining plate fits. An upwardly turned offset flange 8 at the top of the lining plate interlocks with and beneath the corresponding flange on the front plate, but the two plates are otherwise fastened and held together by bolts 9 that may be formed from the ends of a preferably horizontally disposed handle bar or drawer pull 10 located on the outside of the wall in the usual position. The lining plate is preferably embossed at 11 to take the attachment 75 of these bolts.

The drawer casing, indicated generally at 12, comprises top and bottom cross pieces 13 and 14 constituted in the present instance 85 by channel irons, the lower side of the upper piece 13 at the front of the chamber being provided with an aperture 15 adjacent to the bottom or connecting portion 16 of the channel which latter acts in the capacity of 90 a keeper plate, as will hereinafter appear.

Housed within the hollow front wall 1 of the drawer is a vertically movable latch bolt 17 carried on the lining plate 5 in a guide that I prefer to form by striking up offset 95 lugs or ears 18 from the material of the plate. There is no objection to thus mutilating the lining plate, as it is on the inside of the wall and drawer and not exposed to view or to dust and dirt. At its lower end 100 the bolt is provided with a forwardly extending operating member 19 that projects through a slot 20 in the front plate 4 and becomes accessible at a point adjacent to the handle or pull 10 where it may be conveniently manipulated to release the latch by the same hand that is used to open the drawer and with practically the same movement. In the present instance the latch is released by downward pressure on the op- 110

erating member against the tension of a spring 21, the lower end of which spring is connected to the operating member while the other end is fastened to a hook 22, 5 formed by an extension of one of the guiding ears 18.

At its upper end the bolt passes through a slot or opening 23 in the lining plate 5 that is located adjacent to the offset upper 10 flange 8 thereof and the slot may, in fact, continue through the flange to facilitate assembling the bolt. Beyond the slot the latter is bent rearwardly at 24 and thence upwardly and forwardly at 25. The portion 15 25 enters the aperture 15 when the drawer is closed and serves as a locking part which engages with the keeper 16 on the casing and it will be noticed that the shape of this locking part constitutes the latch an automatic 20 one under the influence of its spring 21.

I claim as my invention:

1. The combination with a drawer casing provided with a keeper on one wall thereof and a drawer in said chamber having a hollow 25 front wall composed of a front plate provided with a slot and a lining plate spaced therefrom and provided with offset ears struck up from the material of the lining plate to constitute a guide, of a latch bolt housed within said wall and supported 30

in the said guide on the lining plate to move vertically into and out of coöperation with the keeper on the casing as a locking means, an operating member for the latch bolt projecting forwardly therefrom through the 35 slot in the front plate to the exterior of the drawer and a spring for returning the latch bolt having one end connected to the operating member and the other to one of the guiding ears on the lining plate. 40

2. The combination with a drawer casing provided with a keeper on one wall thereof and a drawer in said chamber having a hollow front wall composed of a front plate having an inwardly and thence downwardly turned flange and a lining plate arranged in spaced relation to the front plate and having an offset flange interlocked beneath that on the front plate and a slot adjacent to said flange, of a latch bolt housed within the 50 front wall and mounted on the lining plate to extend through its slot in parallelism to but exteriorly of its offset flange, said bolt being movable as a locking means into and out of coöperation with the keeper on the 55 casing.

ALBERT T. WEISS.
